UNITED STATES PATENT OFFICE.

FRANCIS LAWRENCE LANE AND WILLIAM RAINFORTH, OF LEEDS,
ENGLAND.

HYDRAULIC CONTROLLING APPARATUS FOR HYDRAULIC MACHINERY.

SPECIFICATION forming part of Letters Patent No. 730,273, dated June 9, 1903.

Application filed August 21, 1902. Serial No. 120,569. (No model.)

To all whom it may concern:

Be it known that we, FRANCIS LAWRENCE LANE and WILLIAM RAINFORTH, subjects of the King of Great Britain and Ireland, residing at Leeds, England, have invented a new and useful Improvement in and Relating to Hydraulic Controlling Apparatus for Hydraulic Machinery, of which the following is a specification.

10 This invention relates to an improved arrangement for automatically controlling the supply of water at low and high pressure to any kind of hydraulic machine as circumstances may require.

15 In many instances, but chiefly in the case of hydraulic presses or hydraulic riveters, it is found economical to have high and low pressure systems of water-service, so that the tools or like devices may be advanced close 20 to their work under the low-pressure water and the working operation be performed or completed by the high-pressure water. Such an arrangement is useful especially in the case where the main hydraulic plant of an 25 establishment is only suitable for low pressures and its use is supplemented by the provision of local high-pressure devices, such as intensifiers or other equivalent devices for obtaining a local high-pressure service of 30 water.

Our invention has for its object the arrangement of controlling means which have connection with both the high and low pressure services and adapted to automatically 35 regulate the admission of the high-pressure water to the hydraulic machine after the low-pressure water has reached its limit of work.

The principle on which the operation of the invention depends is the equilibrating of 40 the pressure in the various parts of the device and the machine by which it is controlled while under the low-pressure water; and when this has been obtained the said low-pressure water automatically admits the high-pressure

45 water to finish the operation. It is known that a certain relation exists between the velocity of a fluid and its pressure. In other words, for example, the velocity of water from an accumulator or intensifier to a cylinder 50 is great when the pressure in the cylinder is small and decreases proportionately as the

pressure increases until when the velocity is nil the pressure is at its maximum.

To carry our invention into effect, we connect the low-pressure water with the cylinder 55 of machine, and we place a check-valve in the supply-pipe to prevent any backward flow of water from the cylinder into the low-pressure main. We also connect the high-pressure water with the cylinder of the machine 60 through the medium of a control valve or device which will automatically close by the pressure behind it. With the cylinder of the machine we also connect a device, such as a ram or piston in a cylinder, which can be 65 moved against a resistance which may, if necessary, be adjustable. This device when operated by the pressure is adapted to operate the high-pressure control-valve, so as to open the same and admit high-pressure water to the cylinder 70 of the machine. When this is done, the low-pressure check-valve automatically closes and prevents the high-pressure water from entering the low-pressure main. The working or controlling valve operated by the work- 75 man is on the low-pressure service between the check-valve and the cylinder of the machine. When the high-pressure water has done its work, the working valve is reversed in position and the cylinder of the machine 80 is put into communication with the exhaust, and immediately the pressure is reduced in the cylinder the high-pressure valve is released by the automatic control device and closes itself by the pressure in the high-pres- 85 sure main.

We may in some cases make the piston or ram of the control device of differential areas with a means of communication between the two sides thereof, and we may provide means— 90 such as a cock, valve, or other adjustable bypass—for regulating the area of flow in the said means of communication in order to vary the rate of movement of the said piston or ram.

95 In order that the invention may be the better understood, we will now proceed to describe the same in relation to the drawings hereunto annexed, reference being had to the letters marked thereon.

100 Like letters refer to like parts in the various figures.

Figure 1 shows diagrammatically the general arrangement according to this invention of the various elements involved in a hydraulic-tool installation adapted to be operated by high and low pressure systems of hydraulic supply, in which the high and low pressure water pass through the automatic control device. Fig. 2 shows diagrammatically a modified arrangement, in which the control device is situated at the end of the hydraulic service, with the hydraulic cylinder of the machine situated between the operating-valve and control-valve. Fig. 3 is a sectional side elevation of an automatic control-valve, such as indicated in Fig. 1. Fig. 4 is an end elevation of the same.

Referring to Fig. 1, *a* is the low-pressure supply-service, and *b* is the high-pressure supply-service, both of which are connected to their respective sources of hydraulic power. In the low-pressure supply *a* is arranged a back check-valve *c*, which prevents the high-pressure water passing into the low-pressure main, but permitting the low-pressure water to pass under certain circumstances. This check-valve *c* communicates with the automatic control device *d*, consisting in this case of an annular piston *e* with ram *f*, a series of holes *g* being provided through the body of the piston *e* to allow water to pass therethrough. In the high-pressure main *b* another check-valve *h* is arranged, which is adapted to be lifted by the ram *f* when a certain pressure is reached. This valve *h* communicates by a passage *i* with the control device *d*. The operating-valve *j* for controlling the hydraulic machine *k* is placed between the machine *k* and the control device *d*, *l* being the exhaust-pipe from the operating-valve *j*.

The arrangement shown in Fig. 2 is similar to that shown in Fig. 1, with the difference that the control device *d* is connected by a pipe leading to it from the cylinder of the hydraulic machine *k*, so that it is situated at the extreme end of the hydraulic service. The ram *f* has no annular piston, and the pipe from the check-valve *h* is led direct to the cylinder of the hydraulic machine *k*, so that the water does not pass through the control device *d* in its passage to the hydraulic machine.

The action in each case is the same. When the operating-valve is moved to put the hydraulic pressure on the machine, the low-pressure water is admitted until such a time that the water-pressure in the cylinder of the machine reaches a certain amount, when the said pressure, acting on the ram *f*, operates the check-valve *h* and admits the water from the high-pressure main to the machine, the check-valve *c* on the low-pressure main automatically closing against the high-pressure water. When the hydraulic machine has completed its working stroke, the operating-valve *j* is moved to the position so as to place the machine in communication with the exhaust-pipe *l*.

Referring now to Figs. 3 and 4, we there show an automatic control device *d* in detail for use with the arrangement as shown in Fig. 1. The high-pressure water enters the device by the passage *m* and the low-pressure water by the passage *n* and leaves it by the passage *o* on its way to the hydraulic machine. The piston *e* fits the cylinder freely and is provided with grooves *p* to prevent the water passing by too freely. The holes *g* are preferably made oblique to the axis of the piston to carry the piston downward while the low-pressure water is flowing. The ram *f* has an upper stem *q*, which passes through a stuffing-box to the under side of the valve *h*. The water from this valve passes down a central hole *r* in the stem and ram to the upper side of the piston *e*, or equivalently it can pass by the pipe *i*, in which is preferably inserted a regulating-valve *s* to control the rate of admission of the high-pressure water to the control device. A spiral spring *t* is disposed between the ram and the fixed upper part of the device and a lever *u*, with counterbalance *v*, is arranged to act on the ram in order to provide means for regulating the amount of resistance to the movement of the ram *f* according to circumstances.

Having now described our invention, what we claim, and desire to secure by Letters Patent, is—

1. In combination with the low and high pressure service-pipe, a control device comprising a cylinder, a piston therein arranged to receive the low-pressure water on one side and an outlet for the water on the other side of the piston, oblique ports through the piston, a check-valve in the low-pressure pipe, a valve in the high-pressure pipe and a connection between the piston and the high-pressure valve, substantially as described.

2. In apparatus for automatically controlling the supply of high and low pressure water to hydraulic machinery, an automatic control device consisting of a cylinder, a freely-working annular piston with ram working in said cylinder, a low-pressure inlet to the annular piston in said cylinder, a check-valve controlling the admission of low-pressure water to said cylinder, in combination with a high-pressure inlet to said cylinder, a control-valve on said inlet, means for connecting the said cylinder with the hydraulic machine and means for operating the said high-pressure control-valve by the said ram when the water-pressure from the low-pressure main has been equilibrated in the hydraulic system of the hydraulic machine, substantially as described.

3. In combination with a ram a low-pressure supply, a high-pressure supply, a check-valve in the low-pressure supply, a valve in the high-pressure supply, a cylinder to which both the high and the low pressure supplies are connected, a piston in the cylinder upon one side of which the entering pressure fluid strikes and from the other side of which the

fluid flows to the ram and a connection between the said piston and the valve in the high-pressure supply, substantially as described.

5. 4. In combination a ram, a high and a low pressure supply-pipe, a cylinder, a piston therein, said cylinder being connected with both the high and low pressure supply-pipes, a check-valve in the low-pressure pipe, a valve in the high-pressure pipe connected with the piston in the cylinder, a connection between the cylinder and ram and a weighted lever for applying pressure to the piston, substantially as described.

15 5. In combination a ram, a low-pressure supply-pipe, a high-pressure supply-pipe, a check-valve in the low-pressure supply-pipe,

a valve in the high-pressure supply-pipe, a cylinder connected with the ram, a piston in the cylinder to receive back pressure from the ram, said piston being connected with the valve in the high-pressure pipe and receiving on its face opposite to that receiving the back pressure the velocity of the fluid from the high-pressure supply, substantially as described.

In witness whereof we have hereunto set our hands in presence of two witnesses.
